ELECTRONIC DEVICE HAVING A METAL COLLAR AND DISCAL RING SUPPORTING AN ELECTRODE FROM A RESONATOR

Albert J. Furst, Newark, and Jens J. Aakjær and Paul M. Dickerson, East Orange, N. J., assignors to Westinghouse Electric Corporation, East Pittsburgh, Pa., a corporation of Pennsylvania

Application February 25, 1944, Serial No. 523,830

2 Claims. (Cl. 315—5)

1
This invention relates to electronic devices, and more particularly to the mounting of the electrode therein which is opposed to the cathode.

Particular application of the present invention has been made in an ultra high frequency device identified as a "klystron" and while the invention may be utilized in other electronic devices, for purposes of illustration it is here shown in connection with the reflector electrode of a reflex "klystron" in the accompanying drawing.

Precision of coaxial alignment of a reflector electrode or the like in an ultra high frequency device, such as referred to above, has been found to be highly critical, and heretofore much time and effort in the fabrication of those devices has been devoted to securing the alignment required. Common manufacturing procedure heretofore has been to bend the supporting lead for the reflector or similar electrode back and forth while the said reflector and its attached mounting means are rotated until the reflector comes into axial alignment and rotates on the lathe without wobbling. This not only involves time and labor, but the bending of the lead is detrimental thereto, lessening its inherent rigidity, and thereby increases the likelihood of the reflector being jarred out of alignment in use. The process as heretofore practiced furthermore leaves the collector exposed after its alignment has been effected since it must go from the lathe operator to the workman completing the assembly by subsequent operations. In this interval, which may include a period in storage and other handling, it is not only possible, but has proven to be a fact, that reflector alignment is disturbed. Discovery of the out-of-alignment condition developing after removal from the lathe cannot be readily determined until the electronic device is completed and tested. This involves a very considerable discard of assembled devices, and represents time and material uselessly expended.

The present invention, in its most general aspect, seeks to overcome the deficiencies of the prior art practice and product.

Also, generally viewed, the invention has for objects to provide a device as characterized wherein the reflector or the like is perfectly aligned and by a process which effects the alignment readily and without introduction of bending strains and weakening operations on the supporting lead to the reflector.

More specifically, objects of the invention are to secure alignment of the reflector before it is fixed in its housing and to secure the reflector

2
while positively positioned and held in alignment in its housing.

Further objects of the invention are to provide an improved seal, and sealing procedure for the lead-in and support for the reflector.

A still further object of the invention is to reduce the number of parts and of operations from prior art practice in effecting the seal.

Another object of the invention is to accomplish the alignment and mounting of the reflector during the concurrent assembly of the complete device and by the operator performing the assembly operation and in any event as one of the final steps of assembly to avoid possibility of loss of alignment after being once attained.

Other objects of the invention will appear to those skilled in the art as the description progresses, both by direct recitation therein and by implication from the context.

Referring to the accompanying drawing in which like numerals of reference indicate similar parts throughout the several views:

Figure 1 is a longitudinal sectional view of a reflex Klystron illustrative of an electronic device embodying our invention;

Figure 2 is a sectional view of the insulating crown or flare by which the reflector lead-in is supported and sealed in place, showing the said crown or flare prior to and ready for use;

Figure 3 is an elevation of the reflector-housing unit of which said crown constitutes one part;

Figure 4 is an elevation of the reflector-electrode unit; and

Figure 5 is a sectional view of the said units, shown separately in Figures 3 and 4, situated in position for final unification and assembly.

In the specific embodiment of the invention illustrated in said drawing, there is shown a beam type electronic device generally defined as

40 a reflex Klystron fabricated as a body of revolution about an axis and providing a coaxial hollow body 10 forming a resonant chamber 11 therein with a cathode 12 on a common axis with and adjacent the chamber, and an opposed reflector

45 electrode 13 also on the same axis at the other side of said chamber 11. Passageway for a coaxial electron beam is provided through said chamber from the cathode to the reflector.

The specific showing herein of the hollow body 50 resonator comprises a cylindrical wall 14 to one end of which is sealed a circularly corrugated flexible end wall 16. Protruding coaxially through the flexible end wall 16 is a tube 17 the inner opening through which constitutes part 55 of the aforementioned passageway from cathode

to reflector. The end of said tube 17 within the resonator chamber is parallel and proximate to the rigid flat end wall 15. The other end of said tube outside the resonator chamber has a flange 18 radiating therefrom spaced from and in parallelism to the general plane of the corrugated wall. This flange is seated in and sealed at its rim to the inner periphery of a flanged ring 19. A coaxial and sealed cathode housing is likewise secured to said ring, as shown more fully in co-pending application of J. M. Carter, Serial No. 485,852, filed May 6, 1943, and assigned to the same assignee as the present invention.

A similar flanged ring 20 is provided at the far side of the rigid end wall 15, sealed thereto. The flanges of said rings 19, 20 project radially further from the common axis than the cylindrical wall 14 of the resonator body, and are maintained in spaced and substantially parallel relation by struts 21, underlying one of which is an adjusting or tuning lever 22 as more fully described and claimed in a copending application of William W. Rigrod, Serial No. 503,189, filed September 21, 1943, and now U. S. Patent No. 2,439,908, granted April 20, 1948, and also assigned to the same assignee as the present invention. The plates are drawn toward each other and against the struts by a plurality of tension springs 23.

Appropriate grids are interposed in the passageway between the cathode and reflector, one grid 24 being situated across the end of tube 17 next the cathode, parallel thereto, and another grid 25 is situated at the other or inner end of the tube, whereas a third grid 26 is shown across the opening through rigid end wall 15 of the resonator, all of said grids being substantially parallel to each other and coaxial to the common axis thereof and which is coincident with the axis of the resonator. An output loop 27 is shown at one side of the resonator appropriately sealed in the outer member 28 of the usual form of coaxial line conductor.

Mounting of the reflector electrode 13 constituting an essential feature of the present invention is obtained by means of a crown or flare 29 of insulating material, preferably borosilicate glass, which has a large mouth or rim 30 of cylindrical configuration sealed to a collar 31 of suitable material. By preference an alloy known in the trade as "Kovar" more fully described in patent to Howard Scott, No. 2,062,335 of December 1, 1936, and assigned to the same assignee as the present invention, is used as the material constituting said collar. Said collar is cylindrical and coaxially mounted on the outer discal face of ring 20 to which it is sealed, such mounting being performed prior to securing the ring upon the resonator body. Said ring 20, collar 31 and crown are assembled as a reflector-housing unit, such unit being illustrated in Figure 3, ready to receive the reflector.

The reflector electrode 13 is shown of cup formation with the hollow of the cup directed toward the cathode. From the other or what may be termed the back side of the cupped part of the reflector is a stiff and rigid lead-in wire 32 constituting also a support for the reflector, said wire being straight and of appropriate length to extend axially of the collar and crown and project from the outer end or center of the crown while positioning the reflector electrode approximately at the level of said ring. The reflector cup and lead-in wire are preassembled as a unit before introduction into the reflector-housing unit, said reflector unit also preferably including

5 a glass bead 33 at the part thereof designed to pass through the crown or flare. Said bead is of an appropriate material, such as glass, having a coefficient of expansion substantially equal to that of the wire on which it is applied.

10 The crown 29 converges to a mid-part of the end thereof away from the collar and is provided thereat with a protruding hollow neck 34 the hole 35 through which is of appropriate size to freely admit the bead 33 of the electrode unit therein. When proper alignment and positioning of the electrode unit is effected with respect to the reflector-housing unit, the glass of the said neck and of said bead are fused together or otherwise unified, and the reflector thereby held rigidly in its assembled relation to the collar and ring.

15 In order to obtain and maintain precise coaxial alignment of the reflector housing unit and the electrode unit until the above-mentioned unification is accomplished and alignment and support thereby rendered permanent, a jig 36 is provided shown in Figure 5. Said jig comprises a stepped plate, the larger step 37 of which is cylindrical and fits accurately in the cut-out or socket prepared in the ring 20 for ultimately receiving the rigid wall of the resonator body. The next 20 smaller step 38 of the jig is likewise cylindrical and made to fit in the opening through said ring, and the final and smallest step 39 is likewise cylindrical and formed to accurately fit within the cup-shape of the reflector electrode. All of 25 said cylindrical steps of the jig are coaxial so that when applied to the two units those units are of necessity in proper and coaxial relation. 30 It is while said units are thus held, that the sealing of the glass of the neck 34 of the crown to the glass bead of the electrode unit is effected. The jig is then removed and the assembly seated on and sealed to the resonator body.

35 40 We claim:

1. An electronic device comprising a cathode and an opposed electrode axially aligned therewith; a cavity resonator having an end wall between said cathode and electrode transverse to the axis of said cathode and electrode; means supporting and enclosing said electrode comprising a stem extending from the electrode in a direction away from the cathode, a glass dome sealed to a part of said stem distant from said electrode, and a metal collar coaxially around said electrode having one rim directed away from the cathode and sealed to the margin of said dome and having its other rim directed toward the cathode in a common plane with the edge 45 of said electrode toward the cathode; and a discal ring interposed between said resonator wall and rim of said collar and defining the spacing of said wall and electrode and projecting radially outward from said collar and from said wall and providing support both for the resonator and for the said means.

50 55 60 65 70 75 2. An electronic device comprising a cathode and an opposed electrode axially aligned therewith; a cavity resonator having an end wall between said cathode and electrode transverse to the axis of said cathode and electrode; means supporting and enclosing said electrode comprising a stem extending from the electrode in a direction away from the cathode, a metal collar coaxially around said electrode having one rim directed away from the cathode and its other rim directed toward the cathode and in a plane common with the edge of said electrode toward the cathode, and a glass seal interposed between said stem and said collar; and a discal ring interposed

between said resonator wall and collar and maintaining fixed spacing of said wall and electrode and projecting radially outward from said collar and from said wall and providing support both for the resonator and for the said means, said discal ring having projections on opposite faces thereof and centering said ring with respect to both the collar and the resonator wall.
